DESIGN FOR A FISHING LURE

Arthur C. Clasen, Kansas City, Kans., and Hugh J. Millgard, Spokane, and Theodore A. Phelps, Seattle, Wash.

Application August 27, 1946, Serial No. 132,896

Term of patent 14 years

(Cl. D31—4)

To all whom it may concern:

Be it known that Arthur C. Clasen, residing at Kansas City, county of Wyandotte, Kansas; Hugh J. Millgard, residing at Spokane, county of Spokane, Washington; and Theodore A. Phelps, residing at Seattle, county of King, Washington; all of whom are citizens of the United States, have invented a new, original, and ornamental Design for a Fishing Lure, of which the following is a specification, reference being had to the accompanying drawing, forming a part thereof, in which:

Fig. 1 is a perspective view showing the bottom side of a fishing lure, showing our new design;

Fig. 2 is a side elevational view of the fishing lure;

Fig. 3 is a bottom plan view of the same;

Fig. 4 is a front elevational view of the same; and

Fig. 5 is a top plan view of the same.

In Figs. 1, 2, 3, and 5, the lining is to represent contrasting colors.

We claim:

The ornamental design for a fishing lure, as shown and described.

ARTHUR C. CLASEN.
HUGH J. MILLGARD.
THEODORE A. PHELPS.
